UNITED STATES PATENT OFFICE.

PHILIP H. SPAULDING, OF HINSDALE, ILLINOIS.

END-GATE FASTENER.

1,312,279.

Specification of Letters Patent. Patented Aug. 5, 1919.

Application filed November 27, 1916. Serial No. 133,646.

To all whom it may concern:

Be it known that I, PHILIP H. SPAULDING, a citizen of the United States, residing at Hinsdale, in the county of DuPage, State of Illinois, have invented certain new and useful Improvements in End-Gate Fasteners; and I do hereby declare the following to be a full, clear, and exact description of the invention, such as will enable others skilled in the art to which it appertains to make and use the same.

This invention relates to improvements in wagon end gates, and particularly to a novel means for holding the gate in closed position, and the sides of the wagon box closely gripped therewith.

One object of the present invention is to provide a novel means for holding a wagon box and end gate together, which can be easily inserted and removed when the wagon is within a shed or other structure in which the side walls are disposed close to the sides of the wagon.

Another object is to provide a device which is simple in construction, and effective and durable in operation.

Other objects and advantages will be apparent from the following description when taken in connection with the accompanying drawing:

In the drawing:

Figure 1 is a side elevation of the rear portion of a wagon equipped with my holder.

Fig. 2 is an elevation of the invention in operative position.

Fig. 3 is an enlarged vertical longitudinal sectional view through the invention taken transversely of the wagon box.

Fig. 4 is a top plan view of the device and rear portion of the wagon box.

Referring particularly to the accompanying drawing, 10 and 11 represent the sides of the wagon, 12 the end gate, and 13 the cleats against which the end gate rests. Formed through the side 10, adjacent the top of the end gate, and outwardly thereof, is an opening 14, through which is disposed the flange or sleeve portion 15 of a plate 16, said plate being countersunk into the side of the wagon box, and secured by means of the rivets 17. Secured to the outer face of the side 11, directly opposite to the opening 14, is a plate 18, on which is formed a staple 19, extending at right angles from the plate and through the opening 19' formed in the

said side. The plate 16 is formed with a vertical elongated opening 16', through which is disposed a flattened bolt 20, said bolt being provided with the partial threads 21, and with which is engaged the nut 22. This nut is formed with laterally extending finger pieces 23, which are weighted, for the purpose of counterbalancing the same. The inner end of the bolt is formed with a keyhole opening 25, while the outer end is formed with a head 24 for retaining the nut in place. Engaged in this opening 25 is the angularly extending end 26 of a rod 27. This end is formed with a lug 28 on its upper side, whereby the rod must be disposed in a vertical position before the end will properly enter the opening. When so entered, the rod is swung downwardly into a horizontal position, whereby the said end is thus effectively prevented from accident, displacement, or disengagement from the opening. The other end of the rod is formed with a hook 29 which is adapted to be engaged with the said staple 19. On the end 80 gate, in position to receive and support the intermediate portion of the rod, are the hook-shaped brackets 30. It will be noted that the nut is engaged on the bolt, outwardly of the side of the box, so that it will bear 85 against the plate 16 when turned.

To remove the device from the wagon, for the purpose of taking out the end gate, the nut is turned outwardly until the rod is sufficiently loosened to permit of the removal 90 of the hook 29 from the staple 19. The rod is then turned, or swung, upwardly until the lug 28 engages or registers with the straight portion of the keyhole opening of the bolt. The angular end of the rod can 95 then be readily withdrawn from the opening. The bolt, together with the nut, can also be removed from the plate 16, thus permitting of the ready removal of the end gate.

An upper gate 12' is used when the upper side boards 10' and 11' are disposed on the wagon box, and the parts of the securing means in connection with this upper gate are represented by characters similar to the 105 first-named parts but these characters are primed, as seen in Figs. 1, 2 and 4.

What is claimed is:

In an end gate fastener, the combination with the sides and end gate of a wagon, 110 said sides being formed with transverse openings, a staple member disposed inwardly

through the opening of one of the sides, a sleeve disposed through the opening of the other side, a flat rod disposed slidably through the said sleeve and having mutilated threads on a portion of its length, the opening through the sleeve being of a shape like that of the cross section of the rod and slightly larger than said section, the inner end of the rod being formed with a longitudinally extending keyhole slot, a nut engaged on the rod outwardly of the

outer end of the sleeve, and a rod having a hook on one end for engagement in the said staple member, and a laterally directed key-head for engagement in the slot of the rod. 15

In testimony whereof, I affix my signature, in the presence of two witnesses.

PHILIP H. SPAULDING.

Witnesses:

LOVILLO G. MITCHELL,
FRANK N. GLASNER.
